FILTER ELEMENT FOR A RESPIRATOR

Leslie Silverman, Dover, Mass., assignor to Welsh Manufacturing Company, a corporation of Rhode Island

Filed Oct. 31, 1963, Ser. No. 77,219

Term of patent 14 years

(Cl. D83—1)

FIG. 1 is a perspective view of a filter element for a respirator showing my new design;

FIG. 2 is a front elevational view thereof;

FIG. 3 is a side elevational view thereof;

FIG. 4 is a sectional view taken on lines 4—4 of FIG. 2; and

FIG. 5 is a sectional view taken on lines 5—5 of FIG. 2.

The rear side of the respirator is plain and unornamented.

I claim:

The ornamental design for a filter element for a respirator, substantially as shown.
